UNITED STATES PATENT OFFICE

104,527

DESIGN FOR A GAME BOARD

Howard H. Brown, Providence, R. I.

Application March 17, 1937, Serial No. 68,214

Term of patent 7 years

To all whom it may concern:

Be it known that Howard H. Brown, a citizen of the United States, residing at Providence, in the county of Providence and State of Rhode Island, has invented a new, original, and ornamental Design for a Game Board, of which the following is a specification, reference being had to the accompanying drawing, forming a part thereof.

Fig. 1 is a plan view of a game board embodying my new design.

Fig. 2 is an edge view thereof.

I claim:

The ornamental design for a game board substantially as shown.

HOWARD H. BROWN.
